DESIGN FOR A BACK FOR A WALLET OR SIMILAR ARTICLE

Morris R. Helfgott, Brooklyn, N. Y.

Application February 28, 1945, Serial No. 118,178

Term of patent 3½ years

(Cl. D87—3)

To all whom it may concern:

Be it known that I, Morris R. Helfgott, a citizen of the United States, residing at Brooklyn, New York, in the county of Kings and State of New York, have invented a new, original, and ornamental Design for a Back for a Wallet or Similar Article, of which the following is a specification, reference being had to the accompanying drawing, forming a part thereof.

In the drawing:

Fig. 1 is a front perspective view of a back for a wallet or similar article, showing my new design; and

Fig. 2 is a rear perspective view of the same.
I claim:

The ornamental design for a back for a wallet or similar article, as shown.

MORRIS R. HELFGOTT.
